UNITED STATES PATENT OFFICE.

JOHN H. WRIGHT, OF DECATUR, GEORGIA.

DESIGN FOR A BOTTLE.

Application filed April 23, 1926. Serial No. 17,420. Term of patent 7 years.

To all whom it may concern:

Be it known that I, JOHN H. WRIGHT, a citizen of the United States, residing at 556 Church Street, city of Decatur, in the county of Dekalb and State of Georgia, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

JOHN H. WRIGHT.
